ATTORNEY

UNITED STATES PATENT OFFICE.

EDWARD R. PETRIE, OF NEW YORK, N. Y.

WHISTLE.

Application filed September 24, 1926. Serial No. 137,428.

This invention relates to whistles and particularly to devices of this class provided with means for mounting the same upon the body of a person and particularly the finger of a hand; and the object of the invention is to provide a whistle of the class specified composed of a plurality of sheet metal parts fashioned and secured together to form a substantially unitary body and a finger ring or loop on said body, the several parts of the whistle being so constructed as to permit of the manufacture and sale of the device at a nominal cost and yet produce a strong, durable whistle structure and one involving the desired tone and tone quality characteristics; a further object being to provide a whistle of the class specified with an adjustable finger ring or loop whereby the whistle body proper may be moved into different positions with relation to said ring or loop for convenient use upon the hand of the operator; a still further object being to provide a whistle having two or more whistle chambers or bodies producing in a single unitary construction, whistles of two tone characteristics or qualities, as for example, the tone values of what is known as a police whistle and the tone values of a traffic or signal whistle whereby the single body is adapted for a double use or purpose; and with these and other objects in view, the invention consists in a whistle of the class and for the purpose specified, which is simple in construction, efficient in use, and which is constructed as hereinafter described and claimed.

The invention is fully disclosed in the following specification, of which the accompanying drawing forms a part, in which the separate parts of my improvement are designated by suitable reference characteristics in each of the views, and in which:—

Fig. 1 is a longitudinal sectional view through one form of whistle made according to my invention.

Fig. 2 is a section on the line 2—2 of Fig. 1.

Fig. 3 is a plan view of a blank from which one part of the whistle shown in Figs. 1 and 2 is formed.

Fig. 4 is a plan view of a blank from which the other part of the whistle shown in said figures is formed.

Fig. 5 is a view similar to Fig. 1 but showing a modification.

Fig. 6 is a plan view of a dual whistle body which I may employ.

Fig. 7 is a longitudinal section of the whistle shown in Fig. 6; and

Fig. 8 is a partial section on the line 8—8 of Fig. 7.

In forming the whistle shown in Figs. 1 and 2 of the drawing, I employ two blanks 10 and 11, the blank 10 being shown in Fig. 3, and consists of an elongated body of sheet metal, one end 10^a of which is provided with laterally directed members 10^b. Adjacent the end 10^a is a part 10^c foldable on the line 10^d and fashioned to form a curved lip portion of said part 10^c in the resulting whistle. Another part 10^e is foldable on the line 10^f to form of said part, a beveled wall. Another part 10^g is foldable on the line 10^h and extends onto the part 10^a and at right angles thereto as clearly seen in Fig. 1 of the drawing to form a stop wall to limit the forward movement of a ball or other member 12 disposed within the whistle body as seen in Fig. 1.

It will be understood that the part 10 constitutes the lower structure of the resulting whistle body and the projecting members 10^b are curved downwardly and inwardly to form thereof an open finger loop or ring 13. The body 10^a is also preferably curved upwardly to form on the lower face of the resulting whistle body, a convex recess extending longitudinally thereof to fit the contour of the finger of a hand. It will be understood, at this time, that the members 10^b are movable toward and from each other and possess a certain amount of spring properties for adjustment of the whistle device to fingers of different sizes.

The top or cover structure of the whistle body is fashioned from the blank 11 shown in Fig. 4 of the drawing which is in the form of a rectangular body 11^a having a projecting tongue 11^b at one side thereof, and the body 11^a is drawn in cup fashion to form therewith a chamber 14. Said chamber is closed by the body 10^a and the parts foldable thereon. The body 11^a is provided adjacent the projecting tongue 11^b with an arc-shaped aperture 15 through which the sound passes,

the aperture being smaller than the ball or other member 12 employed to prevent the displacement of the ball from the chamber 14 as will be apparent. The projecting tongue part 11^b is curved laterally and rests upon and is secured to the lip portion 10^c and the bevel wall 10^e, said wall extending upwardly and inwardly to form at the inner end of the projecting tongue 11^b a comparatively narrow discharge aperture 16 whereby a blast of air blown through the opening 17 in the lip portion of the whistle formed by the parts 10^c and 11^b is discharged into the chamber 14 of the whistle body and moves the ball 12 in said body to cause a loud blast, this result being also accomplished in the passage of the air over the beveled edge 18 formed around the aperture 15 in the body 11^a of the whistle.

In Fig. 5 of the drawing, I have shown a slight modification in which I have substituted for the parts 10^c, 10^e and 10^g on the body 10^a of the whistle, two parts 19 and 20, the part 10 being foldable at right angles to the body 10^a of the whistle to form a stop wall for the ball 12 similar to the wall 10^e, and the part 20 extends from the discharge aperture 16 outwardly and downwardly to form in conjunction with the part 11^b, the mouthpiece of the whistle. Otherwise, the whistle shown in Fig. 5 is of the same structure as that shown in Figs. 1 and 2 of the drawing.

In Figs. 6, 7 and 8 of the drawing, I have shown another modification wherein I provide an elongated whistle body 21, one end of which is fashioned to form a single whistle chamber 22 having a mouth piece portion 23, similar in construction to the mouthpiece portion shown in the whistle body illustrated in Fig. 1 of the drawing, the chamber 22 containing a movable ball or other body 24. Disposed at the opposite end of the body 22 are two chambers 25 and 25^a which open outwardly in one mouthpiece portion 26 and are subdivided by a central partition wall 27 which extends into the inner end portion of the chambers 25—25^a as seen in Fig. 7 of the drawing. Inwardly of the mouthpiece 26 are two sound discharge apertures 28 and 29 disposed at different points with relation to the end of the mouth piece 26 and opening into the separate chambers 25 and 25^a whereby a blast of air entering the aperture in the mouthpiece 26 and the separate chambers 25 and 25^a will produce in a single operation, two differential tone whistle sounds common in what is known as police whistles.

The chambers 25 and 25^a are separated from the chamber 22 by a partition wall 30 seen in Fig. 7 of the drawing. It will be noted that the partition wall 30 is arc-shaped in form, the concave face being directed to the chamber 22 whereby in the operation of the

whistle, the ball or spherical member 24 will be whirled in said chamber to produce a loud vibratory blast, it being understood that the whistle blasts from the chamber 22 pass outwardly through an aperture 31 in the whistle body adjacent the mouthpiece 23. The several parts of the whistle may be constructed in any desired manner and of any number of parts which may be welded, soldered or otherwise secured together as is also true in securing the parts of the whistles shown in Figs. 1 to 5 inclusive.

In Figs. 6, 7 and 8, I have also shown a finger ring or loop 32 which is pivoted substantially centrally of the whistle body 21 or the lower face thereof, the ring or loop 32 being of the split type to form independently adjustable members 32^a to adapt the same for use on fingers of different sizes. This ring or loop is pivotally mounted in connection with the body 22 as seen at 33 whereby the same may be adjusted into different angular relations with reference to said body to dispose the mouthpieces 23 and 26 in desired relation with reference to the hand, to facilitate the use of the whistle.

It will be understood that an adjustable finger ring or loop may be incorporated with a single whistle body as well as with the double whistle body as seen in Figs. 6, 7 and 8 of the drawing, and also a solid or otherwise constructed finger loop may be employed in connection with the dual whistle body, and various other changes in and modifications of the construction herein shown and described may be made within the scope of the appended claims without departing from the spirit of my invention or sacrificing its advantages.

Having fully described my invention, what I claim as new and desire to secure by Letters Patent, is:

1. A whistle of the class described comprising a hollow body, a mouthpiece portion at one end of said body and opening thereto, and a mounting ring or loop comprising relatively adjustable arc-shaped members, said ring or loop being pivotally supported in connection with the whistle body whereby said body is adjustable thereon.

2. A whistle of the class described comprising a hollow body, a mouthpiece portion at one end of said body and opening thereto, and a mounting ring or loop comprising relatively adjustable arc-shaped members, said ring or loop being pivotally supported in connection with the whistle body whereby said body is adjustable thereon, another mouthpiece at the other end of said body, and means for dividing said body into independent sound chambers.

3. A whistle of the class described comprising a hollow body, a mouthpiece por-

tion at one end of said body and opening thereinto, and a mounting ring or loop comprising relatively adjustable arc-shaped members, said ring or loop being pivotally supported in connection with the whistle body whereby said body is adjustable thereon, another mouthpiece at the other end of said body, means for dividing said body into independent sound chambers disposed at the opposite ends of the body, and one of said sound chambers being subdivided longitudinally thereof to form at one end of the whistle body, a two tone whistle.

4. A whistle body fashioned from two sheet metal parts, one of said parts being cup-shaped in form and providing a hollow body portion having a projecting lip member at one end thereof, and an aperture in the top wall of said body adjacent said lip member, the other part forming a plate for closing the open end of the hollow body and having a lip member cooperating with the lip member of the first named part to form in conjunction therewith a mouthpiece, the lip members of said parts being fashioned to form a conical aperture, the contracted end of which opens into said hollow body adjacent the aperture in the top wall thereof, a mounting member on the whistle body and comprising relatively adjustable arc-shaped portions projecting from the lower face of the whistle body, said mouthpiece being arranged at one end of the whistle body and the other end of said body having a mouthpiece opening into two sound chambers independent of the first named chamber.

5. A whistle device fashioned from two sheet metal parts, each of said sheet metal parts having a mouthpiece portion forming when said parts are secured together, a mouthpiece end portion, one of said parts being box-shaped in form and secured to the other part to form a chamber therebetween, into which the mouthpiece opens, and said box-shaped part having an aperture for the discharge of air blown into said chamber through said mouthpiece, the mouthpiece end portion of one of said parts consisting of a plurality of foldable plate members, one of which forms at the inner end of the mouthpiece, a comparatively narrow discharge aperture opening into the first named aperture, and another of said plate members forming a stop wall at one end of said chamber for a movable member contained within the chamber of the whistle device, another mouthpiece portion on said whistle device and means for dividing said chamber into separate parts to form independent sound chambers with which the separate mouthpieces communicate, one of said sound chambers being divided centrally and longitudinally to form two sound chambers thereof, and apertures on the whistle body arranged at different distances from one of the mouthpieces, and opening into the last named chambers.

6. A whistle device fashioned from two sheet metal parts, each of said sheet metal parts having a mouthpiece portion forming when said parts are secured together, a mouthpiece end portion, one of said parts

being box-shaped in form and secured to the other part to form a chamber therebetween, into which the mouthpiece opens, and said box-shaped part having an aperture for the discharge of air blown into said chamber through said mouthpiece, the mouthpiece end portion of one of said parts consisting of a plurality of foldable plate members, one of which forms at the inner end of the mouthpiece, a comparatively narrow discharge aperture opening into the first named aperture, and another of said plate members forming a stop wall at one end of said chamber for a movable member contained within the chamber of the whistle device, another mouthpiece portion on said whistle device, and means for dividing said chamber into separate parts to form independent sound chambers with which the separate mouthpieces communicate.

7. A whistle device fashioned from two sheet metal parts, each of said sheet metal parts having a mouthpiece portion forming when said parts are secured together, a mouthpiece end portion, one of said parts being box-shaped in form and secured to the other part to form a chamber therebetween, into which the mouthpiece opens, and said box-shaped part having an aperture for the discharge of air blown into said chamber through said mouthpiece, the mouthpiece end portion of one of said parts consisting of a plurality of foldable plate members, one of which forms at the inner end of the mouthpiece, a comparatively narrow discharge aperture opening into the first named aperture, and another of said plate members forming a stop wall at one end of said chamber for a movable member contained within the chamber of the whistle device, another mouthpiece portion on said whistle device and means for dividing said chamber into separate parts to form independent sound chambers with which the separate mouthpieces communicate, one of said sound chambers being divided centrally and longitudinally to form two sound chambers thereof, and apertures on the whistle body arranged at different distances from one of the mouthpieces, and opening into the last named chambers.

8. A whistle device fashioned from two elongated sheet metal parts, one of said parts being in the form of an elongated cup-shaped hollow body having substantially parallel side walls, a top wall and one end wall, the side walls of said body at the open end thereof being cut away to form of said side walls and a part of the top wall, a projecting lip member, the top wall being provided with an aperture adjacent said lip member, the other part being fashioned to conform with the contour of the exposed edges of the end and side walls of the first named part forming

a closure for said hollow body and having a lip member cooperating with the lip member of the first named part to form in conjunction therewith a mouthpiece, and the lip member of the last named part including a part extending into said mouthpiece at an inclination to the top wall of the first named

part to form a conical aperture, the contracted end of which opens into the hollow body adjacent the aperture in said top wall. 10

In testimony that I claim the foregoing as my invention I have signed my name this 21st day of Sept., 1926.

EDWARD R. PETRIE.
